United States Patent

Des. 235,980

Patented July 22, 1975

235,980

REFLECTOR

Gerald Golden, Highland Park, Ill., assignor to
Beatrice Foods Co., Elgin, Ill.

Filed Aug. 7, 1974, Ser. No. 495,400

Term of patent 14 years

Int. Cl. D10—06

U.S. CL D10—111

FIG. 1 is a front elevational view of a reflector embodying the design;

FIG. 2 is a rear elevational view of a reflector embodying the design;

FIG. 3 is a top plan view of the reflector illustrated in FIGS. 1 and 2; and

FIG. 4 is a bottom plan view of the reflector illustrated in FIGS. 1 and 2; and

FIG. 5 is a side elevational view of the reflector illustrated in FIGS. 1 and 2.

The oblique line shading indicates a reflective surface.

I claim:

The ornamental design for a reflector, substantially as shown and described.
